UNITED STATES PATENT OFFICE.

WILHELM PEINEKE, OF BERLIN, GERMANY, ASSIGNOR TO SIEMENS-SCHUCKERT-WERKE AKTIENGESELLSCHAFT, OF BERLIN-SIEMENSSTADT, GERMANY, A CORPORATION OF GERMANY.

ELECTRIC INDIVIDUAL DRIVE FOR SPINDLES.

Application filed March 17, 1928, Serial No. 262,464, and in Germany March 24, 1927.

My invention relates to an electric individual drive for the spindles of spinning machines, artificial silk centrifugals, spinning pots and other bodies revolving at high speeds. In mechanical drives of this kind the rotation of the driving machine is generally transmitted to the spindle or the like by means of pulleys and belts or cords. When the electric drive was adopted the pulley on the spindle was replaced by an electric motor and the shaft of this motor was joined to the spindle. The motor which in this design of the machine is located above the spindle rail is rather in the way of the working spindle. It becomes, furthermore, quickly soiled by fluff and dust and is also exposed to mechanical damage. Owing to the extremely high speeds the bearing becomes very hot and provisions must be made for cooling the bearing as well as the entire motor, since the motor is fed with alternating current of high frequency and becomes heated by far more than a normal motor.

My invention relates to an electric individual spindle drive with vertical shaft, which is suitable for very high speeds, of the order of 20,000 revolutions per minute. My invention consists in locating the electric motor, the upwardly extending shaft of which serves as spindle, underneath the spindle rail and drawing the cooling air through ducts or channels at the motor frame and the wall of the bearing and ejecting it into the atmosphere by means of a screen disc mounted on the spindle shaft.

Since the fly-wheel effect of the bobbin placed upon the spindle and the motor armature is, as a rule, very small, any small eccentric irregularity of the bobbin or spool becomes noticeable by the unsteady run of the spindle. Preferably the spinning spindle is rendered indifferent against such disturbing unbalances by an additional disc flywheel.

Since the spinning spindles are subject to considerable wear in consequence of their very high speeds, care must be taken to permit a convenient replacement of defective spindles by other spindles, a large number of which is preferably kept in readiness. An easy exchange of the spinning spindles is according to my invention rendered possible by securing the spindle, inserted into a recess of the spindle rail in its working posi-

tion, by spring pressure only and without the use of screws or the like. In this way the further advantage is obtained that the place of attachment located between the spindle and the motor is elastic, so that the spindle revolving at a high speed is free to set itself in the correct working position. The complete spindle together with its motor may furthermore be bodily removed from the spindle rail without the necessity of loosening any screw connections. The electric connection of the motor to the supply system is effected by elastic contact members, which in the operative position abut against the busbars.

Various embodiments of my invention are illustrated in the drawings affixed hereto and forming part of my specification. In these drawings

Fig. 1 represents an elevation, partly in section, of my improved individual spindle drive,

Fig. 2, a modified detail, and

Fig. 3, a further modification of my improved drive.

Referring to Fig. 1 of the drawings, 1 is the driving motor vertically mounted in an opening of the spindle rail 3 by means of a flange 2. The shaft 4 of the motor is extended upward and designed as spindle, being, for instance, provided with a tube 5 for spooling a thread or filament. The spindle is journaled in the bearing 7. Since the motor is fed by alternating current of high frequency, a considerable heat is developed in the bearing owing to the reversal of magnetism as well as the high speed, which heat is removed by the cooling fins or ribs 6 on the motor casing which along the bearing 7 form closed channels or ducts 8. Above the bearing 7 is located the screen disc 9 which owing to the high speed of rotation has a strongly exhausting action and thus draws the air through the channels in the motor casing and the ducts in the bearing so that the motor and the bearing are efficiently cooled. The disc 9 consists preferably of sheet steel and need not be provided with fan blades as it revolves at such a high speed that even the smooth surface entrains the air and a sufficient circulation of the air is set up in this way.

In the design illustrated in Fig. 2 the screen disc has a comparatively considerable

thickness, so that it acts like a flywheel and thus compensates any unbalanced condition of the spindle which may exist. To reduce mechanical material stresses the mass of the disc is reduced in thickness at the circumference.

Fig. 3 of the drawings shows a spinning spindle secured in easily exchangeable manner in the spindle rail 13, and maintained in working position by springs 18. These springs 18 are attached to the flanges 12 fixed upon the casing of motor 11 and upon the end of the bearing 17 and engage a recessed portion 16 in the spindle rail 13 when the spindle occupies its working position. The supply of current to the motor takes place by means of the busbars 21 located underneath the spindle rail 13. Against these bus bars 21 are placed the elastic contacts 22 connected to the terminals of the motor 11, so that the motor is at once connected to the busbars when the spindle is pushed into the opening in the spindle rail. Upon the casing of the motor 11 is also mounted the push-button switch 23. The spindle 14 carrying the bobbin 15 is provided with a disc 19 acting as flywheel. The rotor of the driving motor 11 is not as in Fig. 1 freely suspended, but is supported at the bottom in the lower bearing 20 of the motor casing besides being journaled in the spindle bearing 17 at the top. For the efficient cooling of these two bearings and of the motor the cooling ribs upon the casing of the motor 11 are surrounded by a shell or jacket 24, so that closed channels or ducts are formed through which the cooling air sucked in by the disc flywheel 19 sweeps and thus effectively cools the lower motor bearing 20, the motor 11, as well as the upper spindle bearing 17.

The elastic attachment of the spindle in the spindle rail enables the axis of the spindle to set itself in the correct position, which is of vital importance for the steady run of the spindle at the high velocities attained. The arrangement illustrated in Fig. 3 has the further advantage that the entire electric portion is completely separated from the spindle, so that the spindle may be easily attended to, while unintentional contact with current carrying parts is effectively avoided.

Various modifications and changes may be made without departing from the spirit and scope of the invention, and I desire, therefore, that only such limitations shall be placed thereon as are imposed by the prior art.

I claim as my invention:

1. In an electric high speed individual spindle drive, in combination, a spindle rail, an electric motor having an upwardly extended vertical shaft end serving as spinning spindle, a bearing located between said motor and said spindle and having air cool-

ing ducts provided at its outside, a shell enclosing said ducts and having a flange for attaching the entire drive to said spindle rail, and a screening disc mounted upon said shaft between the spindle and said bearing and adapted to draw air through the cooling ducts of said bearing.

2. In an electric high speed individual spindle drive, in combination, a spindle rail, an electric motor having an upwardly extended vertical shaft end serving as spinning spindle, a bearing located between said motor and said spindle having air cooling ducts provided at its outside, a shell enclosing said ducts and having a flange for attaching the entire drive to said spindle rail, and a screening disc mounted upon said shaft between the spindle and said bearing, said disc being designed as flywheel and adapted to draw air through the cooling ducts of said bearing.

3. In an electric high speed individual spindle drive, in combination, a spindle rail, an electric motor having an upwardly extended vertical shaft end serving as spinning spindle, a bearing located between said motor and said spindle and having air cooling ducts provided at its outside, a shell enclosing said ducts and having two flanges, said spindle rail having an opening for receiving the drive between said two flanges, springs mounted upon said flanges adapted to maintain the driving device elastically in position, and a screen disc mounted on the said spindle above said bearing and adapted to draw air through the cooling ducts.

4. In an electric high speed individual spindle drive, in combination, a spindle rail, an electric motor having an upwardly extended vertical shaft end serving as spinning spindle, a bearing located between said motor and said spindle and having air cooling ducts provided at its outside, a shell enclosing said ducts and having two flanges, said spindle rail having an opening for receiving the drive between said two flanges, springs mounted upon said flanges adapted to maintain the driving device elastically in position, and a screen disc mounted on the said spindle above said bearing and adapted to draw air through the cooling ducts, elastic contact elements mounted upon the motor frame and being connected to the motor winding, and bus bars located underneath the spindle rail against which said elastic contacts are adapted to abut for supplying the motor with current.

5. In an electric high speed individual spindle drive, in combination, a spindle rail, an electric motor having an upwardly extended vertical shaft end serving as spinning spindle, a shell surrounding the motor and being spaced from the motor to form passages for cooling air, a bearing located between said motor and said spindle and

being provided at the outside with ducts for the cooling air, a shell surrounding said ducts and having a flange, said spindle rail having an opening for receiving said driving device between said flange and said motor, said flange forming a continuation of the shell surrounding said bearing ducts and said motor, a screen disc mounted on the spindle above the said bearing and adapted to draw the air through the cooling ducts ¹⁰ of the bearing as well as through the passages formed between said shell and the motor casing.

In testimony whereof I affix my signature

WILHELM PEINEKE.
